UNITED STATES PATENT OFFICE.

SAMUEL BARKER, OF PROVIDENCE, RHODE ISLAND.

BLEACHING-MACHINE.

1,173,160.

Specification of Letters Patent. Patented Feb. 29, 1916.

Application filed November 10, 1914. Serial No. 871,383.

To all whom it may concern:

Be it known that I, SAMUEL BARKER, a subject of Great Britain, residing at Providence, in the county of Providence and State of Rhode Island, have invented a new and useful Improvement in Bleaching-Machines, of which the following is a specification.

My invention has reference to an improvement in bleaching machines and more particularly to an improvement in that form of bleaching machine in which the bleaching liquor is drawn from the tank and forced through the beam, cheeses, etc., into the tank, the flow then reversed and the bleaching liquor drawn from the beam, cheeses, etc., and forced into the tank.

In the usual construction of such bleaching machines as heretofore constructed, the beam, cheeses, cops, etc., are usually held in a vertical position and in an entirely inclosed keir or vat, also a centrifugal pump and a plurality of valves are usually used to control and reverse the flow of the bleaching liquor.

The object of my invention is to improve the construction of a bleaching machine whereby a clamping device at one end of a beam clamps the opposite end of the beam practically directly to a rotary pump.

Another object of my invention is to provide a twin open top tank bleaching machine for bleaching comparatively small amounts of stock or for sample bleaching, whereby one or both tanks may be used, a beam may be bleached in one tank and a plurality of cheeses in the other tank or either tank may be used for bleaching beans, cheeses, cops, cones, crosswound bobbins or small beams.

Further objects of my invention are to simplify the construction and operation of a bleaching machine whereby all valves are eliminated, beam, cheese and cop bleaching is greatly improved and the bleaching liquor and time heretofore required materially reduced.

My invention consists in the peculiar and novel construction of a valveless bleaching machine, said bleaching machine having details of construction, as will be more fully set forth hereinafter and claimed.

Figure 1 is a top plan view of my improved twin bleaching machine. Fig. 2, is a side view of the machine partly in section. Fig. 3, is a vertical transverse sec-

tional view taken on line 3.3. of Fig. 1, through the machine. Fig. 4, is an enlarged detail sectional view of part of the spindle box and showing one of the perforated spindles for holding the cheeses, cops, bobbins, etc. Fig. 5, is a side view of a dummy beam used when only one tank is in operation. Fig. 6, is an end view of the dummy beam, and Fig. 7, is a face view of a rubber disk used in connection with the dummy beam.

In the drawings, 8 indicates an end frame supporting two horizontal parallel screw clamps 9, each of which are in screw-threaded engagement with a nut member 10 secured to the frame 8. Each screw clamp 9 has a hand wheel 11 on its outer end and a clamping head 12 on its inner end provided with a packing ring in its face. A reversible rotary pump 13 of any usual construction is placed at the end opposite the frame 8. A twin tank 14 closed at the bottom, sides and ends and open at the top and forming two open top bleaching compartments 15, 15, is supported intermediate the end frame 8 and the rotary pump 13, at one end by the frame 8 and at the opposite end by a V shaped pipe fitting 16, which operatively connects the pump 13 with each of the open top bleaching compartments 15, 15. A pipe 17 leads from the fitting 16 to a reserve tank, not shown, by which the bleaching liquor may be drawn from the machine when required. A head 18, having a packing ring in its face is connected by a pipe 19, to each inner end of the fitting 16, in the end of the tank and on a straight axial line with its corresponding head 12, on the clamp screw 9. A pipe 20 operatively connects the pump 13 with a V shaped pipe fitting 21 which in turn is connected by pipes 22, 22 to the bottom of each of the tanks 15, 15.

For bleaching yarn in the beam, the usual beam 23 having a hollow perforated center and open ends is used, as shown in Fig. 2. For bleaching yarn in the form of cheeses, cops, cones, or crosswound bobbins, my improved spindle box is used. This spindle box 24 as shown in Figs. 1, 3 and 4, consists of a hollow rectangular shaped closed box, approximately the same length as the beam 23, and having the flanged pipe openings 25, 25 at each end and a plurality of outwardly extending hollow perforated spindles 26, 26 on each side, on which the

cheeses 27.27 are frictionally secured. The hollow center of these spindles 26.26, connects with the interior of the spindle box, as shown in Fig. 4.

- 5 When only one bleaching compartment 15 is required for use, the opening into the pipe 22, in the bottom is plugged up and a dummy beam 28 having the length of a beam and flanged ends 29.29, is used in
 10 place of a beam and a soft rubber washer 30 is placed between the end 29, and the opening in the pipe 19, thereby closing up both openings into the compartment, not used.
 15 Either one or both bleaching compartments may be used at any one time, any combination of beams, cheeses, cops, cones, crosswound bobbins or small beams, (by using a short dummy beam) may be
 20 bleached at any one time. When only one compartment is used only one half the quantity of bleaching liquor is required and only one quart of bleaching liquor is required per pound of yarn.
 25 In the operation of my improved bleaching machine a beam 23 may be secured in one compartment 15, with one open end of the beam on the face of the head 18, over the opening in the pipe 19, and the other
 30 end of the beam against the face of the head 12. The beam is now firmly clamped in place against the head 18 by turning up the screw clamp 9, and a spindle box 24 carrying a plurality of cheeses 27.27, may
 35 be secured in place in the other compartment in the same way. A comparatively small amount of bleaching liquor approximately fifteen gallons is placed in each compartment 15.15, and the rotary pump 13 operated to draw the liquor from the bottom of each compartment through the pipes 22,
 40 21, 20 and pump 13, and force the liquor through the pipes 16 and 19 and then through the beam 23 and the spindle box
 45 24, perforated spindles 26.26, and cheeses 27.27 back into the compartments. This circulation of the bleaching liquor, as indicated by the arrows in full lines, in Fig. 2, is kept up for a predetermined length of
 50 time, the pump then reversed, the bleaching liquor forced to flow in the reverse directions, that is to say, from the beam and cheeses back into the compartments, as indicated by the arrows in dotted lines in
 55 Fig. 2. This forward and reverse flow of the bleaching liquor is continued until the bleaching process is completed in a comparatively short period of time.

Having thus described my invention, I
 60 claim as new:—

1. A valveless bleaching machine com-

prising a frame, a reversible rotary pump, an open top tank intermediate the frame and the pump, a lower pipe connecting the pump with the tank, an upper pipe connecting the pump with the tank and means for clamping the end of a hollow perforated beam in the tank to the upper pipe whereby bleaching liquor may be forced through the beam in opposite directions without the use 70 of valves.

2. A valveless bleaching machine comprising an end frame, a reversible rotary pump at the opposite end, an open top tank intermediate the end frame and the pump, 75 a pipe connecting the pump with the bottom of the tank, a pipe connecting the pump with the end of the tank, and means for clamping the end of a hollow perforated beam in the tank to the end of the 80 pipe in the end of the tank whereby bleaching liquor may be forced through the beam from the center or from the outside of the beam without the use of valves.

3. A valveless bleaching machine comprising an end frame, a horizontal clamping mechanism on the end frame and having a clamping head in the face of which is a packing ring, a reversible rotary pump at the opposite end, an open top tank intermediate the end frame and the pump, a pipe connecting the pump with the bottom of the tank, a pipe connecting the pump with the end of the tank, a pipe connection in the end of the tank and having a flanged 95 end in the face of which is a packing ring, and a pipe connecting with the pipe leading into the end of the tank whereby the flow of bleaching liquor through a hollow perforated beam in the tank may be reversed and all valves heretofore used for this purpose eliminated.

4. In a valveless bleaching machine, an open top tank, a reversible rotary pump, a pipe connecting the pump with the bottom of the tank, a pipe connecting the pump with the end of the tank and means for clamping the open end of a hollow perforated beam to the pipe in the end of the tank, whereby said tank, beam, rotary pump and pipes form a complete reversible circulating system through which a bleaching liquor may be forced in either direction, without the use of valves.

In testimony whereof, I have signed my name to this specification in the presence of two subscribing witnesses.

SAMUEL BARKER.
